UNITED STATES PATENT OFFICE.

EDWARD E. RICE, OF ELMIRA, NEW YORK.

STONE-CREASING TOOL.

1,296,317.

Specification of Letters Patent.

Patented Mar. 4, 1919.

Application filed April 25, 1916. Serial No. 93,516.

To all whom it may concern:

Be it known that I, EDWARD E. RICE, a citizen of the United States, residing at Elmira, in the county of Chemung and 5 State of New York, have invented a new and useful Stone-Creasing Tool, of which the following is a specification.

The device forming the subject matter of the application is adapted to be employed 10 for grooving glass-cutting stones with grit, and the invention aims to improve the tread surface of a device of the kind mentioned, so that the same will be unusually effective in operation.

15 It is within the province of the disclosure to improve generally and to enhance the utility of devices of that type to which the present invention appertains.

With the above and other objects in view 20 which will appear as the description proceeds, the invention resides in the combination and arrangement of parts and in the details of construction hereinafter described and claimed, it being understood that 25 changes in the precise embodiment of the invention herein disclosed can be made within the scope of what is claimed, without departing from the spirit of the invention.

In the accompanying drawings:—

30 Fig. 1 shows in side elevation, a device constructed in accordance with the present invention, parts being broken away;

Fig. 2 is a top plan of the structure shown in Fig. 1;

35 Fig. 3 is a top plan wherein parts appear in section;

Fig. 4 is a cross section showing a modified form of creasing wheel;

Fig. 5 is a cross section showing a still 40 further modification in the creasing wheel;

Fig. 6 is a side elevation showing a modified form of the invention;

Fig. 7 is an elevation of the wheel shown in Fig. 6;

45 Fig. 8 is a cross section on the line 8—8 of Fig. 6;

Fig. 9 is an elevation showing a modified form of the invention;

Fig. 10 is an elevation showing a further 50 modification of the invention;

Fig. 11 is a cross section showing a further modification in the invention.

In carrying out the present invention there is provided a holder 1 in the form of a 55 rod or bar. The holder may be variously

constructed at its ends. Both ends of the holder 1 may be fashioned as hereinafter described or, if desired, but one end of the holder may embody the construction set forth herein.

In the end of the holder there are formed 60 rectangularly disposed notches 2 and 3, the notches 2 and 3 defining what may be denominated upper arms 4 and lower arms 5. If desired, but one set of arms may be provided at the end of the holder 1. The arms 4 and 5 are provided with openings 6 into which are threaded screws 7 provided at their inner ends with conical bearing points 8. On the outer ends of the screws 7, lock 70 nuts 9 are threaded, the lock nuts engaging the outer faces of the arms 4—4 or 5—5. The outer ends of the elements 7 may be provided with screw-driver kerfs 10.

The invention comprises a creasing wheel 75 11 equipped with circumscribing recesses 14, and a flat band 15 between the recesses 14. The entire periphery of the wheel 11 is circumscribed by sharpened ribs 16 which form the creases in the stone to be operated upon. Since the wheel 11 is shaped peripherally as shown at 14 and 15, stones having a convex face and stones having a flat face may be creased with equal facility. The wheel 11 includes short hubs 17 and 80 18 through the hubs 17 extends an opening 18 terminating in enlarged recesses 19 in which the bearing points 8 of the screws 7 are received.

It will be obvious that, owing to the provision of the screws 7 one wheel may be substituted readily for another. Further, as hereinbefore stated, owing to the construction of the periphery of the wheel, shown at 14 and 15, stones, the faces of which are 85 shaped differently, may be creased by the wheel forming the subject matter of this application.

In Fig. 5 of the drawings there is shown 90 a creasing wheel 20 having a single facing edge 21, this wheel being adapted for use interchangeably with the wheel 11.

In Fig. 4 of the drawings, a modified wheel 22 is shown, the same having the axial opening 23, the seats 24 and the hubs 25 105 hereinbefore described. In this form of the invention, the wheel is provided with two circumscribing concaved recesses 26 having sharpened circumscribing ribs 27.

In Fig. 6 of the drawings, the holder or 110

bar 101 is provided with arms 102 at both ends. In the arms 102, rectangularly disposed openings 103 and 104 are formed. Axles 105 are mounted in the openings 103 and are held in place by set screws 106, threaded into the openings 104. The inner ends of the axles 105 terminate in points 107 engaged in recesses 108 formed in the hub 109 of a creasing wheel 110 provided with a concaved tread 111 having circumscribing ribs of the sort hereinbefore described. An oil duct 114 communicates with the recesses 108 and in the axles 105 may be formed oil ducts 115.

15 As shown in Fig. 9, the wheel 120 is provided with a convexed tread 121 having ribs of the sort hereinbefore set forth.

In Fig. 10, the wheel 122 has a straight, ribbed tread 123. As shown in Fig. 11, the 20 wheel 122 is devoid of hubs but is provided with conical recesses 124 in its side faces, the recesses 124 being connected by an oil duct 125.

25 In all forms of the invention, the wheels are provided in their tread portions with transverse grooves 126, intersected by enlarged openings 127. The grooves 126 and the openings 127 are adapted to carry off waste material. The grooves 126 and the 30 openings 127 may be used together, or either of them may be employed to the exclusion of the other.

The creasing wheels herein disclosed preferably are made out of hard metal, such as 35 iron or steel. After the creases are worn out of the creasing wheels, the creasing wheels are annealed and set up in a lathe after which the creases are re-turned into the creasing wheels. In the ordinary operation of the structure herein disclosed, a fine 40 grit of some kind and a liquid are used in

order to work properly into the stones while creasing them.

Having thus described the invention, what is claimed is:

1. A device for grooving glass-cutting stones with grit, embodying an inflexible and unyielding wheel provided on its periphery with circumscribing V-shaped ribs disposed at right angles to the axis of the wheel, the 50 periphery of the wheel being equipped with transverse grooves extended from one side face of the wheel to the other, each of the transverse grooves intersecting all of the ribs, the grooves being enlarged intermediate their ends to form circular openings in the tread of the wheel.

2. A device for grooving glass-cutting stones with grit, embodying an inflexible and unyielding wheel provided on its periphery with spaced concaved circumscribing recesses and with a flat circumscribing surface between the recesses, the wheel being provided on its periphery with circumscribing V-shaped ribs disposed at right angles to the 65 axis of the wheel, the periphery of the wheel being equipped with transverse grooves extended from one side face of the wheel to the other, each of the transverse grooves intersecting all of the ribs, the grooves being 70 enlarged intermediate their ends to form spaced approximately circular openings disposed on said flat surface and at the bases of the recesses.

In testimony that I claim the foregoing as 75 my own, I have hereto affixed my signature in the presence of two witnesses.

EDWARD E. RICE.
